UNITED STATES PATENT OFFICE.

ABRAHAM VANDERBEEK, OF HARTFORD, CONNECTICUT.

UNIVERSAL JOINT.

SPECIFICATION forming part of Letters Patent No. 698,159, dated April 22, 1902.

Application filed March 19, 1901. Serial No. 51,922. (No model.)

To all whom it may concern:

Be it known that I, ABRAHAM VANDERBEEK, a citizen of the United States of America, residing at Hartford, in the county of 5 Hartford and State of Connecticut, have invented a certain new and useful Improvement in Universal Joints, of which the following is a description, reference being had to the accompanying drawings, wherein—
10 Figure 1 is a perspective view of a universal joint embodying said improvement. Fig. 2 is a view of the same, partly in section and partly in elevation, with one shaft at right angles to the other. Fig. 3 is a section view on the plane xx of Fig. 2 looking in direction indicated by the arrows. Fig. 4 is a detail view, in central section, of the block. Fig. 5 is a side view of the bifurcations of one shaft with its appurtenant trunnion-shafts
15 in position. Fig. 6 is a view similar to Fig. 3, showing a modification in which the trunnion-shafts are parts of spheres. Fig. 7 is a view similar to Fig. 3, showing a modification in which the trunnion-shafts are regularly cylindrical.

The object of the improvement is the production of what is known as a "universal joint" having features of novelty and advantage whereby one shaft drives another out of 20 alinement with itself. The two shafts are bifurcated at the ends which are joined.

In the accompanying drawings the letter a denotes the bifurcations of one shaft, and b the bifurcations of the other shaft.

25 The letter c denotes what may be termed an "intermediate block." Before the trunnion-sockets are cut in it it is preferably very near like a cube in shape; but the exterior shape is not essential, for it may be varied at 30 pleasure.

The letters d and e denote four trunnion-shafts, which fit into trunnion-sockets which are cut for them in the intermediate block c . The trunnion-shafts d are appurtenant to the 35 bifurcations a and the trunnion-shafts e are appurtenant to the bifurcations b . The trunnion-shafts may be attached to their respective bifurcations in any suitable manner, but preferably as by screws f and g .

50 The letter f denotes two screws appurte-

nant to the bifurcations a . They run through the same. They are threaded into the trunnion-shafts d .

The letter g denotes two screws, which are appurtenant to the bifurcations b . They run 55 through the same. They are threaded into the trunnion-shafts e , and they likewise bear on the central part of the block c . By means of the screws f the trunnion-shafts d can be made to bear against the bifurcations a with 60 any desired pressure, and in like manner by means of the screws g the trunnion-shafts e can be made to bear against the bifurcations b with any desired pressure.

There is a cross-like opening c' in the central part of the block c , which for one thing permits the circulation of the oil.

The letter i denotes two stop-pins, carried respectively by the trunnion-shafts d and e , fitting into coöperating and corresponding 70 mortises in the bifurcations a and b , by means of which the trunnion-shafts d and e are prevented from rotation with reference to the bifurcations a and b .

The letter h denotes an oiling-duct. It contains the spring k , on which rests the ball-valve k' , which is kept from escaping from the oiling-duct by the collar l , suitably fastened in the mouth of the oiling-duct. To oil the device one has but to push the ball-valve down a little with the tip of his oil-can 80 and immediately on the removal of the oil-can the spring pushes the ball-valve back against the collar and closes the mouth of the oiling-duct.

85 The trunnion-shafts of Figs. 1 to 5, inclusive, are conical, those of Fig. 6 are parts of spheres, and those of Fig. 7 are regularly cylindrical.

I claim as my improvement—

90 1. In combination the two bifurcated shafts, the four trunnion-shafts removably but non-rotatably secured thereto, and an intermediate block having four trunnion-shaft bearing-sockets, all substantially as described and for 95 the purposes set forth.

2. In combination the two bifurcated shafts, a trunnion-shaft removably but non-rotatably secured to each fork, an intermediate block having sockets adapted to the shape of the 100

- trunnion-shafts, and also adapted to move back and forth thereon.
3. In combination the bifurcated shafts, a trunnion-shaft removably attached to each fork, interlocking parts on each trunnion-shaft and the fork to which it is attached, and an intermediate block having sockets adapted to receive the trunnion-shafts, substantially as described.
- 10 4. In combination the two bifurcated shafts, a trunnion-shaft secured to each fork thereof by means of a screw, projections on the trunnion-shafts adapted to enter recesses in the forks, an intermediate block having sockets adapted in shape to the shape of the trun-
- nion-shafts and arranged to connect said shafts, substantially as described.
5. In combination the two bifurcated shafts, the trunnion-shafts in the form of truncated cones removably secured to the said forks, an intermediate block having conical sockets adapted to receive and work on said trunnion-shafts, the parts being so arranged that the apices of the conical trunnion-shafts meet at substantially the center of the intermediate block, substantially as described.

ABRAHAM VANDERBEEK.
